UNITED STATES PATENT OFFICE.

ANDREW J. PATTERSON, OF HUNTSVILLE, ALABAMA.

LEVEL AND PLUMB.

SPECIFICATION forming part of Letters Patent No. 760,917, dated May 24, 1904.

Application filed March 17, 1904. Serial No. 198,540. (No model.)

To all whom it may concern:

Be it known that I, ANDREW J. PATTERSON, a citizen of the United States, and a resident of Huntsville, in the county of Madison and State 5 of Alabama, have made certain new and useful Improvements in Levels and Plumbs, of which the following is a specification.

My invention is an improvement in combined levels and plumbs; and the invention 10 consists in certain novel constructions and combinations of parts, as will be hereinafter described and claimed.

In the drawings, Figure 1 is a perspective view of a level embodying my invention. Fig. 15 2 is a longitudinal section of the middle portion thereof, showing the recess for the bob and the stock adjusted to an inclined position. Fig. 3 is a similar section to Fig. 2 with the stock adjusted to serve as a plumb. Fig. 4 is 20 a cross-section on about line 4 4 of Fig. 1. Fig. 5 is a cross-section on about line 5 5 of Fig. 3. Fig. 6 is a detail perspective view of the bob or pendulum, and Fig. 7 is a detail top plan view of the graduated plate.

25 In the construction shown the stock A is provided centrally with a recess A', in which operates the bob or pendulum B and above which is secured the graduated plate C, having a central slot C' graduated on opposite sides 30 to indicate different angles to the horizontal.

As shown, the graduations are on a separate plate C secured to the stock, and this construction is employed when the stock is made of wood. If desired, however, the stock may be 35 made of metal. The graduations include a central zero-point and numbers running in opposite directions therefrom and operating to indicate different angles to which the level may be applied and to indicate any desired 40 angles at which it may be desired to place a beam or other structure. Above and intersecting the recess A' the stock is provided with a transverse opening D, having an opening or slot D' for the pointer of the bob or 45 weight and a line D'' to indicate, in connection with said pointer, when the stock is arranged plumb or in a vertical position. Side openings are provided at a and a', extending from

side to side of the stock, through which the pointer may be seen, as best shown in Figs. 50 1, 2, 3, and 4.

The bob or pendulum B is pivoted at B' within the recess A', has a pointer B'' above the pivot B' and a weight B''' below said pivot, such weight being provided at its lower side 55 with the oppositely-facing shoulders b² and b³, which abut, respectively, against pins E and e to stop the pendulum in the position shown in Fig. 2 or in that shown in Fig. 3, the said stop-pins E and e being so arranged that the 60 pointer or indicating-arm B'' of the pendulum or bob does not engage with the stops E and e, or either of them, in any adjustment of the bob, so that there is no danger whatever of the pointer or indicating-arm being deflected 65 to any degree by contact with the stop devices; but such stopping is effected entirely by the engagement of the heavy weighted end of the bob with the pins, the latter extending from side to side across the recess A', as will 70 be understood from Figs. 2, 3, and 4 of the drawings. The bob may be arranged, as shown in Fig. 1, to indicate a level or horizontal position, at an incline, as shown in Fig. 2, to indicate any suitable angle, and in an 75 upright position, as shown in Fig. 3, to serve as a plumb-bob.

In Fig. 4 I show the special means for effecting the pivotal support of the bob or pendulum. This includes lateral pivot-pins b, 80 projecting from the opposite sides of the pendulum and entering elongated sockets f, formed in the inner ends of screws F, turned through the sides of the stock, as will be understood from Figs. 1 and 4. The sockets f 85 are of uniform diameter and extend for a considerable distance into the screws in such manner as to form long bearings of uniform diameters for the pins on opposite sides of the pendulum or bob. This form of bearing is 90 simple, durable, avoiding wear on the parts, and when once adjusted will last for a long time without requiring any adjustment whatever.

The construction of the level as an entirety 95 is simple, convenient for use, and will be ac-

curate and durable, as will be understood from the drawings and the foregoing description.

Having thus described my invention, what I claim as new, and desire to secure by Letters Patent, is—

The improvement in levels herein described, comprising a stock provided with a recess for the bob or pendulum, and in the same with cross-pins for stopping the bob in different positions and having above said recess a curved graduated face, said stock being also provided with a tranverse opening for use in indicating a vertical line, the bob or pendulum having laterally-projecting pivot-pins of uniform diameter and also having the indicat-

ing pointer or arm, and the weight below the same, said weight being provided on its under side with the oppositely-facing shoulders to engage with the stop-pins in the recess, and the screws turned through the opposite sides of the stock into the recess therein, and provided in their inner ends with sockets extending longitudinally and made of a uniform diameter throughout and adapted to receive the pivot-pin on the bob or pendulum, substantially as set forth.

ANDREW J. PATTERSON.
